UNITED STATES PATENT OFFICE.

VALDEMAR F. LÄSSOE, OF NEW YORK, N. Y., AND LUTHER D. LOVEKIN, OF ARDMORE, PENNSYLVANIA.

OIL-BURNER.

SPECIFICATION forming part of Letters Patent No. 716,724, dated December 23, 1902.

Application filed August 5, 1902. Serial No. 118,469. (No model.)

To all whom it may concern:

Be it known that we, VALDEMAR F. LÄSSOE, of the city, county, and State of New York, and LUTHER D. LOVEKIN, of Ardmore, Montgomery county, State of Pennsylvania, have invented an Improvement in Oil-Burners, of which the following is a specification:

Our invention has reference to oil-burners; and it consists of certain improvements which are fully set forth in the following specification and shown in the accompanying drawings, which form a part thereof.

The object of our invention is to provide a simple and durable construction of burner which has capacity for spraying the oil to be burned by forcing it through a nozzle in a thin sheet or film in a confined chamber and subdividing it by a series of transversely-acting currents of air under pressure, preferably in diagonal directions, which are forced through the chamber so as to produce a spiral or gyrating motion to the finely-divided oil and air beyond the end of the burner and where the mixture is burned.

The burner herein described is especially adapted for use in the system of burning oil as fuel set out in our application, Serial No. 117,673, filed July 30, 1902, a reference to which application will show the manner of supplying the burner with oil and spraying air under pressure, as well as the additional air at lower pressure for combustion purposes, said application clearly illustrating the manner in which we have commercially applied our invention.

In carrying out our invention, forming subject-matter of the present application, we employ an air-tube having its rear end provided with an air-inlet and its forward end with spraying-bushings or transverse plates, one of which has a central aperture for receiving the oil-nozzle and both of which have a series of surrounding spraying-apertures between which the oil is forced in a film and through which the air is forced under pressure and carry the oil with it, said apertures being preferably arranged on an incline or spiral, so as to impart a spiral or gyratory motion to the air and oil, and with said air-tube we combine a central oil-tube having its rear end furnished with a connection for oil and its

forward end with a nozzle fitting the inner bushing, so as to discharge into the chamber between the bushings, and a regulating and spraying rod adjustably secured in the oil-tube for regulating the character of oil film or spray delivered from the nozzle.

Our invention also comprehends details of construction which, together with the above features, will be better understood by reference to the drawings, in which—

Figure 1 is a longitudinal sectional elevation of an oil-burner embodying our improvements. Fig. 2 is a cross-sectional elevation of the oil-nozzle on line *x* *x* of Fig. 1. Fig. 3 is an elevation of the inner bushing. Fig. 4 is a section of same on line *y* *y*. Fig. 5 is an elevation of the outer bushing. Fig. 6 is a section of the same on line *z* *z*, and Fig. 7 is a sectional elevation of the forward end of a modification of the burner.

2 is the air-tube of the burner, through which the air is forced, preferably at about one and one-half pounds pressure. The air is supplied to the tube by an inlet 3 and is discharged at the forward end through apertures 6 in bushings 4 and 4^a, screwed into the end of the tube. The inner of these bushings 4 is recessed on its front surface, preferably in a conical form, and the outer of the bushings 4^a is screwed into the inner bushing and has its rear face made conical, as at 21. In this manner a space or chamber 20 is formed between the two bushings, into which oil is forced from the nozzle 9. The outer bushing 4^a has its front surface recessed, as at 19, and through this the apertures 6^a extend, preferably on an incline toward the axis of the burner and also in a spiral direction, as shown in Fig. 3. The inner bushing 4 has its apertures 6 also preferably inclined and spirally arranged, so as to come into direct alinement with the apertures 6^a, as shown in Fig. 1. In this manner the film of oil, which is spread by impinging upon the conical surface of the bushing 4^a, is struck by the jets of air passing from the tube 2 through the apertures 6 and forced through the apertures 6^a in a finely-subdivided condition. As the sprayed oil leaves the burner it has a rotary or gyrating motion, and this further aids in subdivision and proper admixture of the oil with air.

The oil-nozzle 9 fits into the tapered central aperture 7 of the bushing 4 and has its orifice 14 immediately above the apex of the conical surface of the bushing 4. The nozzle makes a tight joint with the bushing 4, so as not to allow the oil to escape back into the tube 2. The nozzle is fitted on its interior with a star-frame 10, which is clamped in position upon a shoulder by the oil-pipe 8 when 5 screwed in place. The rear end of the oil-pipe is secured to an L-head 11, into which the oil is fed under about fifteen pounds pressure by a pipe 12. Extending through the head 11 and the pipe 8 is a valve-rod 13, the 10 end of which is tapered to form a throttling-valve, with the nozzle 9 to regulate the extent of the orifice 14 for the escape of oil. By adjusting the rod 13 the supply of the oil to the chamber 20 may be varied. The rod 13 is 15 made adjustable by having its rear end screw-threaded, as at 16, and working in the head 11. The extreme rear end of the rod passes through a stuffing-box 15 on the head and is provided with a hand-wheel 17, by which to rotate it for 20 adjustment purposes.

When the oil is forced in the chamber 20 under about fifteen pounds pressure, it is spread and brought to a condition of a very thin film. This is rapidly dissipated into a 25 fine spray by the action of the series of spiral air-jets from the apertures 6 and 6^a, which not only produce the subdivision, but also give to the mixture of air and oil a gyratory motion, as aforesaid, which is important in 30 that it produces the better subdivision, a most intimate admixture with the combustion-air supplied to the furnace from around the burner, and a constantly-shifting flame which secures uniform distribution of the 35 heat within the furnace.

In use the burner fits into the usual furnace or fire-box, the flange 18 on the burner-tube acting as a support and means for securing it in place upon the projecting front of the 5 furnace.

If from any cause the air-pressure at the pipe 3 should be lowered or temporarily shut off, there would be liability of the oil passing from the chamber 20 through the orifice 6 into the air-tube. Under such conditions the oil is run off by jet-cock 22, it being prevented from passing farther back in the air-pipe 3 by the annular wall 23. This wall, as shown, is arranged to the rear of the flange 18 and while shallow enough to collect the oil is not sufficiently high to materially obstruct the air.

The bushings are conveniently made as shown, as they may be accurately made and easily replaced, if injured. We, however, do not restrict ourselves in using the term "bushings" to any special details, but only with the understanding that these parts fill up the front end of the burner, so as to form a transverse closure therefor, with the exception of the spraying-apertures formed in them.

In the modification of our invention shown

in Fig. 7 the bushings have straight holes 6^c and 6^a, respectively, the holes 6^c being parallel to the air-tube 2, and the apertures 6^a being inwardly directed, but not spirally arranged. In this case it is preferable that the apertures 6^c shall be larger than the apertures 6^a to insure a greater force being given to the oil and air in passing through the apertures 6^c. 75

If desired, the apertures 6 and 6^a of the structure shown in Fig. 1 need not be spirally arranged; but we prefer that they shall be so formed. 80

While we prefer the construction shown, the details may be modified without departing from the spirit of the invention.

Having now described our invention, what we claim as new, and desire to secure by Letters Patent, is—

1. In an oil-burner, the combination of an air-tube having its front end closed by a transverse structure having a shallow oil-chamber formed by front and rear walls arranged close together and provided with a circular series of apertures through each of the walls whereby air may be forced from the air-tube through said apertures and oil-chamber, and means for spraying oil under pressure against one 90 of the walls of the oil-chamber whereby it is mechanically subdivided and directed outward toward the apertures so as to meet and be taken up by the air passing through said apertures. 95

2. In an oil-burner, the combination of an air-tube having its front end closed by a transverse structure having an oil-chamber and a series of apertures extending through the front and rear walls of the chamber and spirally arranged, an oil-nozzle opening into the chamber through the rear wall thereof and centrally with respect to the apertures, a valve-rod for controlling the oil passing through the nozzle into the chamber, and a pipe for supplying oil under pressure to the nozzle. 105

3. In an oil-burner, the combination of the air-tube having its front end closed by a transverse structure having an oil-chamber formed 115 with a conical internal surface facing rearward and a series of apertures extending through the front and rear walls of the chamber, an oil-nozzle opening into the chamber through the rear wall thereof and directed 120 toward the apex of the conical surface, a valve-rod for controlling the oil passing through the nozzle into the chamber, and a pipe for supplying oil under pressure to the nozzle. 125

4. In an oil-burner, the combination of the air-tube having its front end closed by a transverse structure having an oil-chamber formed with a conical internal surface facing rearward and a series of apertures extending 130 through the front and rear walls of the chamber and spirally arranged, an oil-nozzle opening into the chamber through the rear wall thereof and centrally with respect to the ap-

5 ertures and directed toward the apex of the conical surface, a valve-rod for controlling the oil passing through the nozzle into the chamber, and a pipe for supplying oil under pressure to the nozzle.

5. In an oil-burner, the combination of an air-tube, a bushing structure fitted into the front end of the air-tube and consisting of a front and back portion forming a shallow oil-chamber between them and having a series of apertures through the front and rear walls, and an oil-nozzle for feeding oil under pressure into the chamber opening into the chamber centrally with respect to the series of apertures whereby the oil is spread in the chamber into a thin film and then atomized by air-jets forced through the apertures.

6. In an oil-burner, the combination of an air-tube, a bushing structure fitted into the front end of the air-tube and consisting of a front and back portion forming a shallow oil-chamber between them and having a series of inwardly-directed apertures through the front and rear walls and opening at the front into a recessed portion so that the several jets may directly impinge upon each other, and an oil-spraying nozzle provided with a valve feeding oil as a spray under pressure into the chamber whereby the oil is spread in the chamber into a thin film and then atomized by air-jets forced through the apertures.

7. In an oil-burner, the combination of an air-tube, a bushing structure fitted into the front end of the air-tube and consisting of a front and back portion forming a shallow oil-chamber between them and having a series of spirally-arranged apertures through the front and rear walls arranged in a circle, and an oil-nozzle for feeding oil under pressure into the chamber arranged centrally with respect to the apertures whereby the oil is spread in the chamber into a thin film and then atomized by air-jets forced through the apertures.

8. In an oil-burner, the combination of an air-tube having an atomizing-chamber at its front end provided with a series of apertures opening through the chamber from the inside of the air-tube to the outside of the atomizing-chamber, an oil-nozzle opening into the rear part of the atomizing-chamber and centrally disposed relating to the series of apertures, an oil-pipe extending through the air-

tube for supplying oil under pressure to the nozzle, and an adjustable valve-rod extending to the atomizing-chamber for controlling the flow of oil through the nozzle.

9. In an oil-burner, the combination of an air-tube having an atomizing-chamber at its front end provided with a series of apertures opening through the chamber from the inside of the air-tube to the outside of the atomizing-chamber and further having the rear part of the said air-tube provided with an inwardly-projecting flange to prevent backward flow of oil in the tube, a petcock to draw off the oil collected in the air-tube, an oil-nozzle opening into the rear part of the atomizing-chamber, an oil-pipe extending through the air-tube for supplying oil under pressure to the nozzle, and an adjustable valve-rod for controlling the flow of oil through the nozzle.

10. In an oil-burner, the combination of an air-tube having an atomizing-chamber at its front end provided with a series of spirally-arranged apertures opening through the chamber from the inside of the air-tube to the outside of the atomizing-chamber the inside apertures being in spiral alinement with the outside apertures, an oil-nozzle opening into the rear part of the atomizing-chamber, an oil-pipe extending through the air-tube for supplying oil under pressure to the nozzle, and an adjustable valve-rod for controlling the flow of oil through the nozzle.

11. In an oil-burner, the combination of the air-tube, a bushing 4 fitting the front end thereof and having a central opening 7 and a series of apertures 6 arranged about the central aperture, a second bushing 4^a secured in the bushing 4 and having a rear conical wall 9^a 21 and a series of apertures 6^a adapted to be in alinement with the apertures 6 the said bushings forming a shallow oil-chamber 20 between them, an oil-nozzle 9 fitting the central opening 7 of the bushing 4, and a valve-rod 9^b 13 for the nozzle.

In testimony of which invention we have hereunto set our hands.
